Inventor,

George Leigh,
by Friend of Lawyer,
Assoc. Attorney.

United States Patent Office.

GEORGE A. LEIGH, OF SPRINGFIELD, ASSIGNOR TO HIMSELF AND SAMUEL E. LEIGH, OF BLOOMINGTON, ILLINOIS.

Letters Patent No. 95,239, dated September 28, 1869.

IMPROVED WASHING-MACHINE.

The Schedule referred to in these Letters Patent and making part of the same.

To all whom it may concern:

Be it known that I, GEORGE A. LEIGH, of Springfield, in the county of Sangamon, and in the State of Illinois, have invented a certain new and useful Improved Washing-Machine; and do hereby declare that the following is a full, clear, and exact description thereof, reference being had to the accompanying drawing, making a part of this specification, in which—

Figure 1 is a vertical longitudinal section of my improved device, and

Figure 2 is a side elevation of the same.

Letters of like name and kind refer to like parts in each of the figures.

My invention relates to a class of devices, termed washing-machines, having for their object the cleansing of clothes; and

It consists in the peculiar construction and arrangement of the several parts, by means of which the desired object is accomplished with less labor, and in a more thorough manner than is possible by the use of machines of ordinary construction.

In the annexed drawing—

A represents the box or reservoir of the washer, having vertical sides, while the ends are shaped, as shown in fig. 1, and provided with a cover, B, hinged at one end to one of said end-pieces.

Placed at a distance of from one to two inches from the bottom of the box is a screen, C, formed of strips of wire, arranged parallel with each other, and secured at their ends to cross-bars, c c, the object of which is to furnish a space beneath the clothes, in which sediment and dirt may settle.

D represents a wash-board or rubber, placed immediately above the screen, and sliding longitudinally within a groove formed by the frame of said screen, and by a strip, a, secured to each side of the box.

Pivoted to one end of said rubber, D, is a lever, E, which is secured or pivoted at its centre to a horizontal shaft, e, and at its upper end to a pitman, F.

The outer end of said pitman is pivoted upon a crank, G, secured to and forming a part of a shaft, H, which is journalled within suitable bearings upon the projecting ends of the box, and operated by means of a crank, I, upon its outer end.

K represents a second or upper rubber, corresponding in size with the lower one hereinbefore described, one end of which is suspended from the cover by means of a chain, L, while the opposite end is suspended from a rod, N, pivoted to said rubber, and to the front end of the pitman F.

As thus arranged, it will be readily seen, that if the shaft H is caused to rotate, the crank G, operating through the pitman F, lever E, and rod N, will impart to the rubbers a reciprocating motion, in opposite directions, so that if suds were supplied to the box, any article of clothing placed between said rubbers would be rapidly cleansed.

In order that greater pressure may be exerted upon the clothes, two spiral springs, M, are secured at one end to the lower side of the cover, and at the opposite end, to a bar, n, placed horizontally and lengthwise of the box A. The length of the springs is such as to cause the cross-bars to bear lightly upon the upper rubber when it is resting upon the lower one, and as the clothes placed between said rubbers vary in thickness, the pressure will correspondingly change.

The weight of the upper rubber, in addition to that of the lid, makes it necessary that some provision be made for raising said cover, and securing it in position.

This object is attained by means of a lever, O, pivoted near its centre to the side of the box, and at its upper end to a rod, P, which is, in turn, pivoted at its opposite end to said cover, so that by depressing the outer end of said lever, the cover is correspondingly raised. A catch upon the inner side of said lever, near its handle, engages with a toothed rack, R, secured to one end of the box, and holds said lever in any position desired.

Having thus fully set forth the nature and merits of my invention,

What I claim as new, and desire to secure by Letters Patent, is—

The within-described washing-machine, consisting of the box A, the cover B, the screen C, the rubbers D and K, operated by means of the lever E, pitman F, crank G, shaft H, and rod N, the chain L, the springs M and M, and the levers O and P, all constructed and arranged substantially as and for the purpose specified.

Also, in combination with the cover B, the devices used for raising and securing the lid in place, consisting of the lever O, the rod P, and the toothed rack R, substantially as herein specified.

In testimony that I claim the foregoing, I have hereunto set my hand, this 22d day of July, 1869.

G. A. LEIGH.
